UNITED STATES PATENT OFFICE.

CHESTER C. OBERLY, OF CHICAGO, ILLINOIS, ASSIGNOR TO THE PULLMAN COMPANY,
OF CHICAGO, ILLINOIS, A CORPORATION OF ILLINOIS

ELECTRIC-LAMP REGULATOR.

1,134,346.

Specification of Letters Patent. Patented Apr. 6, 1915.

Application filed May 4, 1914. Serial No. 836,111.

To all whom it may concern:

Be it known that I, CHESTER C. OBERLY, a citizen of the United States, residing at Chicago, in the county of Cook and State of Illinois, have invented certain new and useful Improvements in Electric-Lamp Regulators, of which the following is a specification.

My invention relates to electric lamp regulators and refers particularly (although not exclusively) to regulators which are used in car lighting systems.

It is well known that in car lighting systems as usually employed the generator which is operated by the travel of the car is used for operating the lamps whenever possible; this generator at the same time serving to charge the storage battery. When the generator is not available for use on account of stoppage or slow speed of the car, the lights are supplied with current from the storage battery.

In connection with the lighting circuit a carbon pile resistance is ordinarily employed for the purpose of regulating and keeping uniform the voltage of current which is supplied to the lamps. In connection with the use of the storage battery, this carbon pile resistance is particularly useful when the battery first begins to discharge after being fully charged, inasmuch as, at this time the voltage is somewhat higher than the normal voltage of the battery and the carbon pile resistance is necessary to cut down this excess voltage.

The voltage of the generator used for the lighting system and for the charging of the storage battery is, of course, considerably higher than the normal voltage of the storage battery, and in order to compensate for this higher voltage when the lights are supplied with current direct from the generator, it is necessary that the carbon pile resistance included in the circuit should offer more resistance than is the case when the lights are supplied with current direct from the battery, in order to cut down the generator voltage to the proper point for the lights.

It is the object of my invention to provide means by which the resistance offered by the carbon pile will be reduced to a minimum when the current for the lamps is supplied by the battery, whereas when the lamps are supplied with current from the

generator the resistance offered by the carbon pile will be immediately increased in order to reduce the generator voltage to the proper point. I accomplish this result by varying the amount of current supplied to the solenoid, or other similar device, which operates the carbon pile, according to whether the current is being supplied from the battery or from the generator.

These and other advantages of my invention and preferred means for accomplishing the results mentioned above will be more readily understood by reference to the accompanying drawing, which illustrates diagrammatically a car lighting system in which my invention is employed.

The generator 10 is of the usual shunt type, and has the field winding 11 and the brushes 12 and 13. The conductor 14 leads from the brush 12 to the automatic switch, represented as a whole by 15. The conductor 14 is connected with the solenoid winding 16 of the switch 15, this winding leading to the switch terminal 17. The conductor 14 is also connected with an auxiliary solenoid winding 18 of the automatic switch 15, this winding 18 being connected with the conductor 19, which in turn is connected with the conductor 20 leading to the brush 13. The conductor 20 also extends to one pole of the storage battery 21. The conductor 22 leads from the terminal 23 of the automatic switch 15 to the one arm of the switch 24 and the conductor 25 leads from the conductor 22 to the second pole of the storage battery 21. The automatic switch 15 is provided with the solenoid armature 26, to which is attached the switch member 27, adapted to form connection between the switch terminals 17 and 23. The conductor 28 leads from the switch member 27 to an intermediate point in the resistance coil 29. One end of the resistance coil 29 is connected with the solenoid winding 30 by means of the conductor 31, and the opposite end is connected with the conductor 32 by means of the conductor 33. The solenoid armature 34 within the solenoid coil 30 is provided at its end with the dash pot 35, and has pivotally connected thereto the bell crank lever 36, one arm of which engages the carbon pile resistance device 37, so that by movement of the bell crank lever 36 the pressure between the carbon disks of the resistance device 37 may be

varied. The conductor 38 leads from conductor 20 to one end of the carbon pile resistance device 37, and the conductor 39 leads from the opposite end of this resistance device to one of the blades of the switch 24. The conductor 40 leads from the conductor 39 to the solenoid winding 30. The lamps 41 are connected in multiple between the conductors 32 and 42, these conductors being brought into electrical connection with the conductors 22 and 39 respectively by means of the switch 24.

Having thus described the various parts which are used in my invention, the operation of the same may readily be understood. When the car in which my improved lighting system is employed is at rest or running at a slow speed, the lamps 41 are supplied with current from the storage battery 21 on closing of the switch 24. The circuit is as follows: Current passes from the positive terminal of the battery 21 through the conductors 20 and 38 to the carbon pile resistance 37, then through the latter, next through the conductor 39 to the conductor 42, then through the lamps 41 to the conductor 32, and then back through the conductors 22 and 25 to the negative pole of the storage battery 21. At the same time there is the following shunt circuit: Current passes from the conductor 39, through the conductor 40 to the solenoid winding 30, thence through the conductor 31 and resistance 29 to the conductor 33 to the conductor 32 and completes the circuit to the negative pole of the battery 21 through the conductors 22 and 25. It will be evident that the higher the voltage of the current coming from the storage battery 21, the greater will be the energization of the solenoid winding 30, with a result that the solenoid armature 34 will be moved up, thereby decreasing the pressure between the disks of the carbon pile resistance 37 and increasing the resistance in the main circuit, in which said carbon pile resistance is included.

When operating the lights from the storage battery, it is very desirable that the resistance in the main circuit should be as low as possible, in order to prevent current losses; and for this reason the entire resistance 29 is included in the shunt circuit, so that the energization of the solenoid winding 30 may be comparatively slight, thereby causing the resistance to be slight in the carbon pile resistance 37.

After the car is started and attains the speed of ten to twelve miles an hour, the current generated in the auxiliary winding 18 of the automatic switch 15 is sufficient to close this switch. The circuit to accomplish this result is as follows: From the brush 12 current passes through the conductor 14 to the solenoid winding 18 and thence through the conductors 19 and 20 to the brush 13.

When the current is sufficiently strong, as just pointed out, to close the automatic switch 15, the switch member 27 engages the switch terminals 17 and 23 and current passes from the conductor 14 through the solenoid winding 16 (thereby still further tending to keep the automatic switch closed) and thence through the switch member 27 and the terminal 23 to the conductor 22. The switch 24 being closed, current passes to the conductor 32, thence through the lamps 41 to the conductor 42, then through the conductor 39 to the carbon pile resistance 37, thence through the conductors 38 and 20 to the brush 13, thereby completing the circuit. At the same time that the lights are operated from the generator, the storage battery 21 is included in the generator circuit through the conductors 25 and 20, thereby causing the battery to become charged. At the same time there is the following shunt circuit: Current from the switch member 27 passes through the conductor 28 to the resistance 29 and then through a portion of the latter and the conductor 31 to the solenoid winding 30, and through the conductor 40 to the conductor 39, thereby completing the shunt circuit. It will be evident that inasmuch as less of the resistance coil 29 is included in the shunt circuit used with the generator than is included in the shunt circuit used with the storage battery that the solenoid winding 30 will be energized to a greater extent and will cause the bell crank lever 36 to decrease the pressure on the disks of the carbon pile resistance 37, thereby increasing the resistance in the main circuit from the generator, with the result that the lamps 41 will be supplied with the proper voltage.

It will be apparent that through the instrumentality of my invention a simple and efficient means is provided for regulating the voltage supplied to the lamps in such manner that when the storage battery is used as a source of supply the current losses from resistance are at the minimum, while when the generator is used the resistance in the main circuit is automatically increased, not only by reason of the higher voltage of the generator, but also by means of including less resistance in the shunt circuit in which the solenoid is included.

It will be apparent to those skilled in the art that many changes could be made in the detail construction of the various parts and their relation without departing from the spirit or scope of my invention.

What I claim is:

1. In an electric lamp regulator, the combination of a variable resistance device adapted for connection in the lighting circuit, actuating means for varying the resistance of said device, and means for selectively changing the action of said actuating

means on changing the source of current supplying said lighting circuit, whereby the resistance of said resistance device will be correspondingly changed, substantially as described.

5. 2. In an electric lamp regulator, the combination of a variable resistance device adapted for connection in the lighting circuit, a solenoid for changing the resistance of said resistance device, resistance means connected in circuit with said solenoid, and means for changing the resistance of said resistance means on changing the source of current supplying said lighting circuit, whereby the resistance of said resistance device will be correspondingly changed, substantially as described.

10. 3. In an electric lamp regulator, the combination of a carbon pile resistance device adapted for connection in the lighting circuit, a solenoid adapted to change the pressure between the carbon units of said device, resistance means included in circuit with said solenoid, and means for changing the amount of resistance of said resistance means on changing the source of current supplying said lighting circuit, whereby the pressure between the carbon units of said resistance device will be correspondingly changed, substantially as described.

15. 4. In an electric lamp regulator, the combination of a carbon pile resistance device adapted for connection with the lighting

circuit, a generator adapted for connection in said circuit, a storage battery in said circuit, a solenoid for controlling the pressure between the carbon units of said resistance device, resistance means connected in circuit with said solenoid, said solenoid and resistance means being in shunt with said lighting circuit, and means for changing the resistance of said resistance means on changing the source of current from said battery to said generator or vice versa, substantially as described.

15. 5. In an electric lamp regulator, the combination of a carbon pile resistance device adapted for connection in the lighting circuit, a generator adapted for connection in said circuit, a storage battery in said circuit, a solenoid for controlling the pressure between the carbon units of said resistance device, a resistance coil included in circuit with said solenoid, said solenoid and resistance coil being in shunt with said lighting circuit, and means for cutting out a portion of said resistance means when said generator is included in said lighting circuit, thereby increasing the actuation of said solenoid and decreasing the pressure between the carbon units of said resistance device, substantially as described.
